LAUNDRY TUB

Bernard E. Mustee, Cleveland, Ohio, assignor to
E. L. Mustee & Sons, Inc., a corporation of Ohio

Application February 6, 1956, Serial No. 40,057

Term of patent 14 years

(Cl. D49—1)

The figure is a perspective view showing the front, top and one side of a laundry tub embodying my new design. The other side is identical. The rear is conventional.

I claim:

The ornamental design for a laundry tub, as shown and described.
